UNITED STATES PATENT OFFICE.

REGINALD WALTER MAUDSLAY, OF COVENTRY, ENGLAND.

ELECTRICALLY-OPERATED WARNING HORN.

Application filed July 15, 1922. Serial No. 575,291.

To all whom it may concern:

Be it known that I, REGINALD WALTER MAUDSLAY, a subject of the King of England, residing at Coventry, in the county of Warwick, England, have invented certain new and useful Improvements in Electrically-Operated Warning Horns, of which the following is a specification.

This invention relates to electrically operated warning horns, and it has for its object to provide a simple arrangement whereby the intensity of the sound produced is readily variable at will, so that, for example, when used upon a motor vehicle, a more subdued warning can be given in a town than would usually be required in the open country.

According to this invention, a resistance is provided in the electrical circuit of the horn, in conjunction with a switch having contact members so arranged and connected with the circuit that the closure of the switch acts first to include the aforesaid resistance, and thereafter, by a further onward movement of the switch member, to cut it out. A press switch preferably is employed and its operation is in conformity with the result desired, that is to say, a light pressure will cause a moderate warning sound, and further and harder pressure of the switch will produce a louder sound.

In the accompanying drawings,

Figure 1 represents diagrammatically one method of carrying out the invention, and Figure 2 is a cross-sectional view of a modified preferred construction, of which Figures 3 and 4, to a smaller scale, are respectively a plan and an elevation of separate parts of the switch.

In the method of carrying out the invention illustrated diagrammatically in Figure 1, the resistance A arranged in a compact form is mounted upon the base B of a press switch having a plunger C, and can readily be applied to an existing circuit. The contacts of the switch consist of three spring blades D, D² and D³, upon which a metal plate or strip C² carried by the push button C is adapted to be pressed by the user against the action of a spring, (not shewn in Figure 1).

Two of these contact blades D, D² lie substantially in the same plane so that a comparatively small movement of the button C causes them to be bridged by the metal plate C² and the leads E, E² to which they are

respectively connected include the current source, the resistance A, and the horn. The third contact blade D³ lies in a plane somewhat beyond that containing the other two D and D², and therefore, to reach it with the metal plate C², further onward movement of the button C is required. The connection of the contact D³ with the circuit is at a position E³ in the lead E which excludes the resistance A, and thus, when the plate C² carried by the press button makes contact with it, the resistance is cut out. It is desirable to notice that the plate C² might, if desired, be in permanent electrical connection with either the lead D or D² when the switch is in the inoperative state.

It will thus be seen that the first movement of the switch is adapted to result in a relatively subdued sound from the horn owing to the presence in the circuit of the resistance A, while further pressure upon the switch button will cut out the resistance and cause the horn to produce its full intensity of sound.

In the modified construction shewn in Figures 2, 3 and 4, the same lettering is employed to denote similar parts, the base B having holes B² for securing it where desired. A central recess B³ is provided to contain the resistance A which latter is wound on a former A². An insulating cap arranged in two layers F, F² closes the recess and forms the contact-carrying member and constitutes at F³ a clip for the ends of the leads E, E². A screw F⁴ extending from the underside of the base B through the centre of the former A² engages the cap F, F² and secures it in position. Upon this cap F is mounted a spring blade G which represents the contact D in Figure 1, and also screws G², G³ which secure the leads E² and E and correspond respectively with the contacts D², D³. The ends A², A³ of the resistance A are connected to the blade G and to the contact screw G³.

A metal dome H encloses the contacts and has lugs H² by which it is secured to the base B. A strip of metal G⁴ bent into Z form provides an electrical connection between the contact screw G² and dome H to which it is secured at the lug H². Above the dome H is the button C carrying from a stem C³ the metal plate C² and normally retracted by the spring C⁴. The plate C², through contact established with the dome H through the stem C³ and spring C⁴, is in

permanent connection with one of the leads E², (the possibility of which was pointed out earlier in the specification.)

The lower end C⁵ of the stem C³ which projects somewhat beyond the plate C², is adapted to bear upon the spring blade contact G when the push button C is depressed and in this way the circuit is closed through the resistance A. Further pressure upon the button C deflects the blade G and causes the plate C² to bear on the contact G³ thus cutting out the resistance A, whereby the current to the horn is increased and a louder note accompanies the greater pressure and movement given to the switch button C. It will be seen that it is immaterial whether or not the plate C² also makes contact with the contact G² when the push button is fully depressed, as electrical connection therewith already exists.

What I claim as my invention and desire to secure by Letters Patent of the United States is:—

1. In an electric switch for use with a warning horn, the combination of a press button, a resistance, a first pair of contacts

adapted when the button is lightly pressed to include in the circuit said resistance, and a second pair of contacts adapted when the button is more firmly pressed to exclude said resistance from the circuit, substantially as set forth.

2. In an electric switch for use with a warning horn, the combination of a base carrying the switch mechanism, a resistance enclosed within said base, resilient contact members upon said base, one set adapted to include said resistance within the circuit and the other set adapted to exclude it therefrom, and a switch-operating member adapted under light pressure to close the contacts including the said resistance within the circuit and thereafter, by a firmer pressure, to cut it out therefrom, substantially as set forth.

In testimony whereof I have signed my name to this specification in the presence of two subscribing witnesses.

REGINALD WALTER MAUDSLAY.
